Manuel C. Rosa

UNITED STATES PATENT OFFICE.

JOSEPH E. LAVIGNE, OF FALL RIVER, MASSACHUSETTS.

TRUCK AND SIMILAR CONVEYANCE.

Application filed July 20, 1926. Serial No. 123,657.

My invention relates to a new and useful improvement in trucks and similar conveyances, of the box-like type that are used in shops and factories for transporting goods, 5 wares and merchandise from one room to another; but more particularly the type of truck having air passages and adapted for holding goods, such as cotton filling, wet wash, etc., while they are being subjected to 10 the humidifying or drying treatment. In practice it is customary to use a truck having its sides perforated with air holes to allow the admission of humid atmosphere, however, such an arrangement does not secure uniform treatment of the filling, inasmuch as the holes are easily blocked. Trucks 15 consisting of sides composed of slats spaced apart to provide longitudinal slits have been used but although affording a good air clearance, are not durable, since the slats are generally secured to corner posts by nails or screws which become disengaged because of the corroding action of the moisture-laden atmosphere or because the nails or 20 screws lack the tensile strength to withstand the pressure to which they are subjected. The great difficulty heretofore encountered with the trucks now in use for steaming or other gas or vapor treatment of goods is that 25 the sides become loose and break away from the corner posts.

An object of my invention is to produce a durable and simple truck adapted to hold and carry goods that are to be subjected to 30 vapor treatment.

A further object of my invention is to produce a truck having slotted openings wherein the members making up the sides of the truck are held in recesses in the corner 35 posts and secured by tie rods running from post to post in pairs.

A still further object of my invention is to provide a truck strongly constructed having non-corrodible metal parts and the sides 40 and corner posts so designed that nails or screws are not necessary to secure the two together.

Other objects and advantages will appear from the description which follows.

Referring now to the drawing:

Fig. 1 is a perspective view of the truck. Fig. 2 is a front elevational view of the end sill showing in dotted lines the longitudi-

dinal groove and the recesses which receive the bottom staves or slats. 55

Fig. 3 is a cross-sectional view taken along line A—A of Fig. 2.

Fig. 4 is a bottom view of one-half of the truck showing the jointures between the end sill and the corner uprights as well as the 60 large cross slats for the attachment of the rollers.

Fig. 5 is a detail view of a corner upright or post showing the lower two slats positioned in the recesses and one slat ready for 65 insertion.

Fig. 6 is an interior view of a lower corner of the truck showing the manner of joining the corner post and end sill.

Similar numerals refer to similar features throughout the several views. 70

As shown in Fig. 1 the truck is a box-like structure having corner posts or uprights 1 with slats 2 on the longer sides and slats 3 on the shorter sides morticed in said posts. 75 More particularly the corner posts or uprights are so constructed that they have a right angular cross section and the two outermost faces 4, 5 (Fig. 5) have spaced openings 6 which serve a purpose to be explained hereinafter. The angle posts are preferably made of a non-corrodible metal such as brass, aluminum or duralumin, but they may be made of any other material. 80

The spaced openings on one face of the corner posts are right angularly disposed to the spaced openings on the other or complementary face. The openings are of such size as to receive the ends of the slats 2 and 3 and as shown, they may be varied according to the needs of the artisan. The ends 7 of the slats 2 and 3 serve as tenons which fit into these openings and when in place the four sides are securely held by means of tie rods 8, 9 which run from post to post, and as shown in Fig. 1 there are two tie rods 8 on the longer sides and only one tie rod 9 on each shorter side. Of course it is clearly understood that the number of tie rods may be varied without departing from the spirit 95 of this invention. The end sills 10 of the truck are made of similar non-corrodible metal or other suitable material and as shown in Fig. 2 are provided with spaced holes, five being shown here. The middle 100 opening 11 is larger in order to accommo-

date a larger slat. A longitudinal groove 12 is provided in the upper part of the sill as shown more clearly in Fig. 3 into which the bottom slat of the end series fits when in place as shown in Fig. 5. The material of which the slats are made may be of cypress, cedar, soft pine or other suitable wood.

As shown in Fig. 4, the bottom of the truck is made up of five slats with a slat 13 in the middle larger than the others. This renders it possible to attach a roller or castor at both ends of the truck. A cross slat 14' is provided which is secured to the outside bottom slats and the middle slat to 15 which two castors or rollers are attached. The castors may be of any suitable material preferably cast iron which is not very expensive and can be removed or replaced easily. The corner posts 1 are cut out at the 20 bottom ends to provide a seat 14 to receive the ends 15 of the end sill as shown in Fig. 4.

The corner posts are angular for the greater part of their extent. However, at 25 the lower ends the angle ceases and the posts are of a square cross section as shown in Fig. 6. Seats 14 are cut out in the bottom surface of this squared portion leaving a ledge 16 having an opening 17 therein 30 through which bolts pass for securing the end sill to the corner posts.

It will be appreciated that a truck constructed in the manner here set forth may be subjected to rigorous treatment, and is 35 particularly serviceable in a moisture laden atmosphere, since the side members are mortised to the corner posts and are not nailed or screwed. The danger is thus obviated that the slats may spring loose from the 40 corner posts as would be the case if they were simply nailed thereto. The tie-rods and the bolts securing the end sills to the corner posts at no place contact or grip the wood, the connections being from metal to metal. If as indicated, the metal parts are 45 made of brass, or other noncorrodible metal, a truck is produced which will render dependable service in a moisture laden atmosphere without weakening or the slats working loose for it is well known that iron 50 undergoes rapid rusting or, chemically speaking, oxidation, and iron nails or other

iron securing means would gradually lose their gripping power with the attendant dismemberment of the truck.

55

All that has been said above in the description of my preferred embodiment is offered by way of illustration and not limitation. I do not wish to be limited to the exact structure of the preferred embodiment shown and described, or to any particular material used in the construction of parts, or to the design of parts, but desire protection as against any variations that fall 60 within the purview of my invention and are 65 within the spirit and scope of the following claims.

What I claim as new is:

1. A truck comprising in combination corner uprights, said corner uprights having ledge portions at the lower extremities thereof forming seats, end sill members, said seats being adapted to receive the ends of said end sill members, said sill members and said uprights having openings therein, stave members composing the sides, said openings being adapted to receive the ends of said stave members, means for joining said uprights together and means for joining said sill members to said uprights.

70

2. A truck of the character described, comprising in combination non-corrodible corner uprights and end sills, each of said corner uprights having right angularly disposed recesses in their opposing end faces, said end sills having recesses in their opposing faces, each of said end sills having a longitudinal groove in the upper edge thereof, the sides and bottom of said truck comprising a plurality of stave members the ends whereof are received in the said recesses in the corner uprights and sill members, the lower edges of the bottom staves of the end stave members being lodged in said longitudinal grooves in the sill members, said stave members being held to said uprights and end sills by means joining the corner uprights together in pairs, and additional means for joining the end sills to said corner uprights.
